(57) **CLAIM**

The ornamental design for a protective case for mobile phone, as shown and described.

DESCRIPTION

FIG. 1 is a front, right and top perspective view of a protective case for mobile phone showing my new design; FIG. 2 is a front elevational view thereof; FIG. 3 is a rear elevational view thereof; FIG. 4 is a left side elevational view thereof; FIG. 5 is a right side elevational view thereof; FIG. 6 is a top plan view thereof; FIG. 7 is a bottom plan view thereof; FIG. 8 is a rear, left and bottom perspective view thereof; and, FIG. 9 is an enlarged front, left-side, and bottom perspective view of an upper corner portion of the protective case. The dot-dash broken line in FIG. 9 delineates a portion of the protective case for mobile phone, including claimed subject matter, that is shown on an enlarged scale in this drawing view. The dashed broken lines throughout the drawing figures depict portions of the protective case for mobile phone, in which the design is embodied, that form no part of the claimed design.
